[57] CLAIM

The ornamental design for a sign, as shown and described.

DESCRIPTION

FIG. 1 is a perspective view of a sign, showing our new design;

FIG. 2 is a side elevational view thereof, all sides being identical;

FIG. 3 is a top plan view thereof;

FIG. 4 is a bottom plan view thereof;

FIG. 5 is a perspective view of a second embodiment of a sign;

FIG. 6 is a side elevational view thereof, all sides being identical;

FIG. 7 is a top plan view thereof;

FIG. 8 is a bottom plan view thereof.

The support post has been fragmentarily shown in FIGS. 2 and 6 for ease of illustration.
